Primary Examiner — Melanie Pellegrini

(57) **CLAIM**

The ornamental design for a pendant as shown and described.

DESCRIPTION

1. Pendant

1.1 : Perspective view 1

1.2 : Perspective view 2

1.3 : Front

1.4 : Back

1.5 : Top

1.6 : Bottom

1.7 : Right

1.8 : Left

1.9 : Reference

The characteristic features of the design reside in the shapes as shown in the reproductions; the broken lines in the reproductions form no part of the claimed design.
